UNITED STATES PATENT OFFICE.

RICHARD E. SCHLETTER, OF PHILADELPHIA, PENNSYLVANIA.

DESIGN FOR A SOCK OR STOCKING.

45,497.

Specification for Design.

Patented Mar. 24, 1914.

Application filed December 4, 1913. Serial No. 804,776. Term of patent 14 years.

To all whom it may concern:

Be it known that I, RICHARD E. SCHLETTER, a subject of the Emperor of Germany, residing at Philadelphia, in the county of Philadelphia and State of Pennsylvania, have invented a new, original, and ornamental Design for a Sock or Stocking, of which the following is a specification, reference being had to the accompanying drawing, forming part thereof.

I claim:

The ornamental design for a sock or stocking as shown.

RICHARD E. SCHLETTER.

Witnesses:

WILLIAM J. JACKSON,
HELEN M. BYRNE.
